STOP MOTION FOR CIRCULAR LOOMS

Edward Vossen, Lynbrook, N. Y., assignor to Stop-Motion Devices Corp., Brooklyn, N. Y., a corporation of New York

Application June 29, 1950, Serial No. 171,131

7 Claims. (Cl. 139—353)

1

This invention relates to new and useful improvements in stop motions for circular looms. This invention particularly applies to a Royle circular loom manufactured by John Royle & Sons in Paterson, New Jersey. Heretofore attempts to equip these looms and other circular looms with stop motions have been unsuccessful because the revolving threads were in inaccessible places. These looms are mainly used to manufacture linen fire hose. They employ 288 stationary threads of yarn which are substantially equally spaced around the fire hose being manufactured, and two revolving spools of yarn. The operation of the loom is very similar to a flat loom because groups of the yarns or threads feeding into the looms are alternately moved up and down, and two revolving spools of thread spin around in the center of the loom laying threads of yarn in between the groups of feeding yarns similar to a shuttle in a flat loom. Because the application of a stop motion to this type of loom in the past has not been successful it is customary for one person to watch two looms and stop them whenever required. The stationary threads are provided with weights which fall down when a thread breaks, or an end appears so that a person can hear this and immediately stop the loom. It is required that the person watch the revolving two spools of thread at the centers of the two looms and consequently the person's head turns back and forth between the two looms all day long. Quite often a break in the revolving spool threads is not instantly detected and then the loom must be turned backwards until the point of damage in the hose is reached before it can be repaired and the loom restarted. While the person is thus repairing one loom the other loom must also be stopped because now it is not being watched.

This invention proposes a stop motion for these particular types of looms so that one person may be employed on a relatively large group of looms and operate them more efficiently than the heretofore one person for two looms. For example, with the automatic stop motion device, in accordance with this invention, one person may be provided with four or six looms, since if the threads of any one loom runs afoul the loom will automatically stop.

This invention contemplates to guard both the stationary threads and the revolving threads with the stop motion.

Another object of this invention is to provide small arcuate contacts which may readily be mounted in the vicinity of the revolving spools

2

and which may easily be engaged by a stationary contact arm so that a circuit may be completed to the revolving stop motion switches arranged to guard the revolving spools of the loom.

5 These looms are provided with arcuate thread spreading bars adjacent the revolving spools to spread the threads and make room for the revolving spools. This invention particularly proposes to mount the arcuate contacts referred to in the previous paragraph, on these arcuate thread spreading bars.

10 These circular looms are also provided with stopping mechanism which includes longitudinally movable control rods. It is proposed to provide a controller associated with these rods by which the rods may be operated automatically in the usual way for stopping the circular loom.

15 The invention also proposes a particularly simple and efficient construction of said controller.

20 Another object of the invention is the construction of a stop motion as described which is simple and durable and which may be manufactured and sold at a reasonable cost.

25 In the accompanying drawing forming a material part of this disclosure:

Fig. 1 is a fragmentary plan view of a circular loom provided with a stop motion constructed in accordance with this invention.

30 Fig. 2 is a fragmentary sectional view of portions of the stop motion device seen as though looking in the direction of the line 2—2 of Fig. 1, but no part of the circular loom has been shown in this view, except for the control rod for stopping the machine.

35 Fig. 3 is a fragmentary enlarged plan view taken on the line 3—3 of Fig. 2, with a part thereof broken away to disclose interior parts.

40 Fig. 4 is a fragmentary perspective view of one of the arcuate contacts used in the device.

45 Fig. 5 is a schematic wiring diagram of the stop motion device.

The new stop motion device, in accordance with this invention, is intended for a circular loom 10 which manufactures a fire hose or other hose 11 at its center. This loom is equipped with a plurality of stationary threads 12 arranged completely around the circumference of the loom and is also provided with two revolving spools 13 of thread. These revolving spools 13 of thread are positioned immediately below revolving arcuate thread spreading bars 14 which spread the threads 12 immediately adjacent the hose 11 so as to make room for the spools 13 to revolve. The 50 details of the circular loom will not be given in

this specification since it forms no part of the invention. However, it is pointed out that the threads 12 are stationary and continuously feed into the loom and are arranged in groups which alternately spread upwards and downwards while the revolving spools 13 lay threads in between the spread threads similar to the shuttle in a flat loom. Furthermore, the circular loom 10 is provided with a stopping mechanism of the usual type, not disclosed on the drawing, except for the longitudinally movable control rod 15. One end of this control rod 15 is provided with a handle 16 by which it is intended to be moved. An operator guarding two adjacent looms keeps one hand on each of the handles 16 and is ready to stop either loom, or both looms at an instant's notice, by longitudinally moving each rod 15.

The new stop motion includes a spring 17 connected with an arm 18 which is pivotally supported at its bottom end by a pintle 19. The top end of the arm 18 pivotally connects with the rod 15. The spring 17 normally urges the rod 15 into its "off" position, which is towards the right.

A sleeve cam or sleeve 20 is fixedly mounted on the rod 15 and is cooperative with a controller 21. This controller includes a normally open push button switch 22 adapted to be held closed by the sleeve 20 when said control rod 15 is in its "on" position. The push button switch 22 is provided with a roller operator 23 which is pushed down by a beveled end portion 24 formed on the sleeve cam 20. In Fig. 2 the dot and dash lines 20 indicate the position of the sleeve cam 20 when the controller rod 15 is in its "on" position.

A latch arm 26 is provided for engaging in back of the sleeve cam 20 for holding said control rod 15 in its "on" position. This latch arm 26 is provided with a top roller 27 which may engage behind the back end of the sleeve cam 20. The front bevel 24 is capable of depressing the roller 27 and thus pivoting the latch arm 26 downwards while the control rod 15 is moved to its "on" position. The latch arm 26 extends into a housing 28 which is stationarily mounted on a portion of the frame 29 of the machine. The inner end of the latch arm 26 is pivotally supported on a pivot 30 mounted within the housing 28.

The latch arm 26 is associated with solenoid control means for moving it into its releasing position. This means includes a bracket 31 attached to the arm 26 and extending downwards and provided with a horizontal pin 32. A bell crank 33 is pivotally mounted at its center upon a pivot 34 mounted within the housing 28. The top arm of the bell crank 33 engages across the top of the pin 32. The other arm of the bell crank 33 connects with the core 36 of a solenoid 37. The arm 26 is provided with a spring bracket 38 to which a spring 39 is attached. This spring 39 has its top end connected with the top of the housing 28. It acts to normally urge the latch arm 26 upwards.

The stop motion is also provided with a relay 40 connected to operate the solenoid 37. The relay 40 has a relay coil 41 in a circuit including in series the switch 22 and the secondary 42 of a transformer 43. The primary 44 of this transformer 43 is connected with an electric circuit 45. The coil 41 is also connected with a plurality of stationary stop motion switch devices 46 and with a contact arm 47 engageable periodically with arcuate contacts 48. These contacts 48 are positioned above the threads of the circular loom.

and are supported on said thread spreading bars 14. Each of the arcuate contacts 48 is provided with a fork construction 49 which are adapted to straddle the spreader bars 14 and by which the arcuate contacts are mounted in position. These arcuate contacts 48 are electrically connected by the leads 50 with revolving stop motion switch devices 51 for protecting the revolving threads from the revolving spools 13 of the machine.

The relay 40 is provided with a switch section 52 controlling a circuit 53 which includes the solenoid 37. One stop motion switch device 46 is needed for each stationary thread of the loom. 15 If the loom has 288 stationary threads then 288 of these devices are required. The stop motion switch devices 46 have their bodies grounded in the usual way and their positive terminals are connected in parallel with each other and in 20 series with the coil 41 of the relay 40. The contact arm 47 is supported on a stationary bracket 55 mounted upon the frame 29 of the loom. This bracket 55 must be insulated from the machine so that the contact arm 47 is not short circuited. 25 The leads 50 connect with the terminals of the revolving stop motion switch devices 51. These switch devices 51 have their bodies grounded in the usual way.

The operation of the stop motion may be understood from the following:

The stop motion is placed into operative position by moving the control rod 15 to its "on" position. When this control rod 15 is so moved the sleeve cam 20 will reach the dot and dash line position 20 shown in Fig. 2, and will be held in this position by the latch arm 26. In this position the sleeve 20 engages the roller 23 and closes the push button switch 22. The circular loom is now operating. If any of the stationary threads 12 break or reach an end, one of the stationary stop motion switch devices 46 will operate to cause a current to flow through the coil 41 of the relay. Similarly, if either of the revolving threads from the revolving spools 13 break, or reach an end, one of the revolving stop motion switch devices 51 will operate to cause a current to flow through the coil 41 of the relay 40. When the coil 41 is energized the switch 52 is closed energizing the solenoid 37 which then draws in its core 36 and pivots the bell crank 33 so that the top arm of the bell crank 33 moves the pin 32 downwards and in this way pivots the latch arm 26 downwards, releasing the sleeve cam 20. Spring 17 immediately moves the control rod 15 into its stop position in which the loom stops. When the control rod 15 moves towards its stop position the sleeve cam 20 will ride off of the roller 23 so that the switch 22 opens and interrupts the flow of current through the closed stop motion switch device 46, or 51 which caused the operation of the stop motion.

While I have illustrated and described the preferred embodiment of my invention, it is to be understood that I do not limit myself to the precise construction herein disclosed and the right is reserved to all changes coming within the scope of the invention as defined in the appended claims.

Having thus described my invention, what I claim as new and desire to secure by United States Letters Patent is:

1. In a stop motion for a circular loom having a self closing stopping mechanism and further- 75 more having revolving arcuate thread spreading

bars to make room for the revolving spools of thread, an electric controller for releasing said stopping mechanism, stationary stop motion switch devices for protecting the stationary threads of said loom and electrically connected to actuate said controller, a stationary contact arm electrically connected with said controller and extending down into the vicinity of said spreading bars, revolving stop motion switch devices for protecting the revolving thread of said loom, and arcuate contacts electrically connected with said revolving stop motion switch devices and positioned above said threads and supported on said thread spreading bars and periodically engaging said contact arm during the revolving of said spreading bars in order to close an electric circuit to said controller for stopping said loom when any one of said revolving stop motion switch devices operates.

2. A stop motion as defined in claim 1 in which said arcuate contacts have forks straddling said spreading bars and by which they are attached to said spreading bars.

3. A stop motion as defined in claim 1 in which said arcuate contacts each has a fork construction by which they are supported on said thread spreading bars.

4. In a stop motion for a circular loom having a stopping mechanism including a longitudinally movable control rod, resilient means urging said control rod into an off position, a sleeve cam on

said rod, a normally open push button switch held closed by said sleeve cam when said control rod is in an on position, a latch arm for engaging in back of said sleeve cam for holding said control rod in its on position, solenoid controlled means for moving said latch arm into releasing position, a plurality of stop motion switch devices electrically connected in a series circuit with said switch, and a relay controlled by said circuit and electrically connected to operate said solenoid controlled means.

5. A stop motion as defined in claim 4, in which said sleeve cam has a beveled end cam surface.

6. A stop motion as defined in claim 4, in which 15 a spring resiliently urges said latch arm into its latching position.

7. A stop motion as defined in claim 4, in which said solenoid controlled means comprises a lever- 20 age system connected with said latch arm and with the core of said solenoid.
